ELECTRIC SIGN

Elmer L. Ballew, Chicago, Ill., assignor of one-half to Robert L. Swats, Chicago, Ill.

Application October 8, 1937, Serial No. 167,920

4 Claims. (Cl. 40—132)

This invention relates to an electric sign.

It is an object of this invention to provide an improved electric sign which is relatively simple and inexpensive in construction and maintenance and efficient in use.

I am aware of the fact that electric signs embodying rotary discs and other movable elements have been used heretofore. However, in so far as I am aware these have generally been concerned with providing spiral or whirling lighting effects. I have found, however, that a novel and interesting sign or display device may be constructed by creating the effect or illusion of a series of what appears to be "balls of light" being projected radially outwardly from the center of the sign toward the periphery thereof, rather than by creating a spiral or whirling effect.

Accordingly, another object of the present invention is to provide a novel electric sign of the so-called "neon" or luminous tube type, embodying a rotary disc, and which is so constructed that when in use it creates the illusion in the eye of an observer of a series of so-called balls of light being thrown radially outwardly from the center of the rotary disc toward the periphery thereof, as if by centrifugal action, much in the manner in which drops of water might be thrown out from a rotating element, by centrifugal force, thereby creating a novel and interesting lighting effect and one which readily attracts the eye and attention of an observer.

A further object of the present invention is to construct one form of the same in such a manner that a continuously moving endless element or belt, which is provided with a row of light-penetrable slots, is caused to move in front of one or a series of so-called neon or luminous tubes, thereby producing the illusion in the eye of an observer of a series of so-called "balls of light" being projected from one edge of the housing toward the other edge thereof, as the endless element or belt is moved continuously in one direction in the housing.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a central vertical sectional view, partly in elevation, of one form of the new sign;

Fig. 2 is a front elevational view thereof;

Fig. 3 is a central vertical sectional view on line 3—3 in Fig. 2;

Fig. 4 is a plan view of a modified form of rotary disc which may be used in the device shown in Figs. 1 to 3, inclusive;

Fig. 5 is a front elevational view of a modified form of the new sign, with a part of the front wall thereof broken away so as to reveal part of the interior thereof; and

Fig. 6 is a fragmentary sectional detail view on line 6—6 in Fig. 5.

One form of the new electric sign is shown in Figs. 1 to 3, inclusive, and is therein generally indicated at 10 and comprises a casing or housing 11 which includes a side wall 12, rear wall 13, and a front wall 14, the latter being preferably in the form of an opaque or painted glass sheet which is held in place by a suitable frame 15, and is provided with a series of radially arranged slots 16, (Fig. 2).

Suitably mounted in the casing or housing 11 is a horizontally extending shaft 17 which is operated by a conventional motor mechanism 18, and mounted on this shaft 17, adjacent the front thereof, is a rotary disc 19 which is shown as being provided with a generally S-shaped slot 20; or, if desired, the disc 19 may be replaced by the disc 21 (Fig. 4) which is provided with the generally clover-shaped design 22; it being noted (Fig. 4) that each of the four (or more) elements in the design is substantially oval-shaped in appearance and more or less resembles a horseshoe in shape, for a reason to be explained presently.

Stationarily mounted in the housing 11, rearwardly of the disc 19, on a suitable frame 25, is a series of radially arranged so-called neon or luminous tubes 30 which are shown as being arranged in two groups 25'—26 and 27—28, the terminals of the group 25'—26 being electrically connected to a transformer 31 and the terminals of the group 27—28 being electrically connected to a transformer 32.

In the use of the form of the invention which is shown in Figs. 1 to 3, inclusive, the gas-conducting or luminous tubes 30 are rendered luminous by current from the transformers 31—32, in a manner which is well understood in the art, and the shaft 17 and disc 19 are rotated by the motor mechanism 18. Accordingly, when the slotted disc 19 is rotated (relatively slowly) in front of the radially arranged luminous tubes 30, and rearwardly of the radially arranged slots or light-penetrable areas in the front wall 14 of the housing 11, the effect that is produced in the eye of an observer is to create the illusion that a series of what may be called, for lack of a better

term, "balls" of light are projected radially outwardly from the axial center of the device which is represented by the shaft 17, toward the periphery thereof. This effect is due, in part, to the motion of the slot 20 in the disc 19 in front of the radially arranged tubes 30, and in part to the fact that because of the opaque front wall only the particular tubes 30 may be seen at one time which are in alignment with the slot 20 in the disc 19 and with the corresponding radial slots 16 in the opaque front wall 14.

While so-called luminous or neon tube signs, employing rotary discs, have been heretofore used I have found that none of these, in so far as I am aware, produces the novel effect which is created by the radial arrangement of the tubes 30 and slots 16 in alignment or registration with each other and on opposite sides of the slotted rotary disc 19, so as to produce an effect which may be described, as stated above, as resembling "balls" of light projected radially outwardly along each of the tubes 30. It will be noted, in this connection, that this effect is obtained only if and when the slotted disc 19 is rotated counterclockwise, (Fig. 2) since in this event the radially inner end portion of the slot 20 in the disc 19 moves in front of, or into registration with, each of the tubes 30 before the radially outer end portion thereof moves into alignment or registration with the same, thereby exposing only part of each tube at one time and gradually exposing each tube radially outwardly from its radially inner end, and thus producing the effect of so-called "balls" of light. The foregoing effect may, of course, be reversed by rotating the disc 19 in the opposite direction (clockwise, Fig. 2), whereupon the so-called "balls" of light will travel inwardly from the radially outer ends of the tubes since in this latter event the radially outer end portion of the slot 20 will move into alignment or registration with each tube 30 prior to the radially inner end portion of the same.

If desired the disc 21 (Fig. 4) may be substituted for the disc 19 and in this event the movement of the so-called "balls" of light will be first radially outwardly (when the disc 21 is rotated counterclockwise, Fig. 4) and then inwardly because of the fact that one side A of each slot 22, by reason of its curvature, will expose the radially inner end portion of each tube 30 first and then the remaining portion of the same, whereas the other side B of each slot 22 will expose the radially outer end of each tube first and then the remaining part of the tube.

While the opaque and slotted front wall 14 has been shown (Fig. 3) as embodied in the form of the invention shown in Figs. 1 to 3, inclusive, this opaque and slotted front wall may be replaced by a plain glass front, if desired, without destroying the novel lighting effect described above, although the effect is somewhat better, sharper, and more distinct, when using the opaque front wall than when omitting it.

A modified form of the present invention is shown in Figs. 5 and 6 of the drawings, is therein generally indicated at 31, and comprises a casing or housing 31', which is somewhat similar to the housing 11, except that the housing 31' includes a front wall 32' which is provided with a transparent window 33. Rotatably mounted in the housing 31' is a horizontal shaft 34 on which is mounted a disc 35 which may be provided with an S-shaped slot 36, such as the slot 16 which is provided in the disc 19 or, if desired, the disc

21 (Fig. 4) may be substituted for the disc 35.

Mounted in the housing 31', rearwardly of the disc 35, is a stationary supporting wall or disc 37 and mounted in this wall 37 is a series of radially arranged rows of light-penetrable elements 5 or glass "buttons" 38, while suitably supported in the housing 31', behind each of the rows of buttons 38, is a light source in the form of a luminous or so-called neon tube 39.

In the use of the form of the invention which is shown in Figs. 5 and 6 the shaft 34 and disc 35 are projected by means of a suitable motor mechanism (not shown), and as the slotted disc 35 is rotated in front of the light-penetrable elements or glass buttons 38 an illusion is created, in 15 the eye of an observer, which is identical to that which is produced by the form of the invention which is shown in Figs. 1 to 3, inclusive.

While I have illustrated and described preferred forms of construction for carrying my invention into effect, these are capable of variation and modification, without departing from the spirit of the invention. I, therefore, do not wish to be limited to the precise details of construction set forth, but desire to avail myself of 25 such variations and modifications as come within the scope of the appended claims.

Having thus described my invention, what I claim as new and desire to protect by Letters Patent is:

1. An electric sign comprising a housing having a series of radially arranged light sources therein, said housing including an opaque front wall provided with a series of radially arranged light-penetrable areas corresponding to, and adapted to 35 register with, the said light sources, an opaque disc rotatably mounted in the said housing between the said front wall and the said light sources and having a light-penetrable area provided therein, and means for rotating the said 40 disc.

2. An electric sign comprising a housing having a series of radially arranged luminous gas-conducting tubes therein, said housing including an opaque front wall provided with a series of radially arranged light-penetrable areas corresponding to, and adapted to register with, the said tubes, an opaque disc rotatably mounted in the said housing between the said front wall and the said tubes and having a slot formed therein, and 45 means for rotating the said disc.

3. An electric sign comprising a housing having a series of radially arranged luminous gas-conducting tubes therein, said housing including an opaque front wall provided with a series of radially arranged light-penetrable areas corresponding to, and adapted to register with, the said tubes, an opaque disc rotatably mounted in the said housing between the said front wall and the said tubes and having a generally S-shaped slot 55 formed therein, and means for rotating the said disc.

4. An electric sign comprising a housing including a transparent front wall, an opaque upright support in the said housing rearwardly of the said front wall, a series of light-penetrable elements mounted in the said support in a predetermined configuration, means located rearwardly of the said elements for illuminating the same, an opaque disc rotatably mounted in the said housing between the said support and the said front wall and having a light-penetrable area 65 therein, and means for rotating the said disc.

ELMER L. BALLEW.
